METHOD AND COMPOSITION FOR INHIBIT-
ING FOAM IN AQUEOUS SYSTEMSLewis O. Gunderson, Park Ridge, Ill., assignor to
Dearborn Chemical Company, Chicago, Ill., a
corporation of IllinoisNo Drawing. Application June 3, 1948,
Serial No. 30,981

7 Claims. (Cl. 252—321)

1

This invention relates to a composition for use in conditioning water for the prevention or reduction of foaming in boilers, for the prevention or reduction of moisture entrainment in steam, for increasing the coefficient of heat transfer in boilers, cooling equipment and heat exchange systems without producing a foaming condition, and for generally improving the character of water for use in steam boilers, heat exchange systems, and the like.

Foaming of boiler water is not, as commonly thought, equivalent to an accumulation of foam on top of the surface of the boiler water. When steam is rapidly withdrawn from a boiler with resultant foaming, there is no water surface within the boiler correlated with the water level indicated in the conventional water glass attached to the boiler. In other words, there is no sharp line of demarcation between solid water and foam in the boiler during rapid steam withdrawal.

The foaming of boiler water is actually a rapid expansion of the water in the steam generating area of the boiler brought about by the fact that rapidly forming small steam bubbles do not coalesce until a definite short time after their formation. Small hydrophobic particles dispersed throughout the body of boiler water may act as nuclei promoting the formation of bubbles, particularly when the pressure is suddenly lowered as large amounts of steam are withdrawn from the boiler. As a consequence, the entire volume of water in the generating area is expanded by myriads of bubbles until the thus formed so-called "light water" may fill the steam space and become entrained with the steam leaving the boiler.

In other words, bubbles need not be particularly stable to cause boiler foaming. The stability of the bubbles need be only such that the bubbles last but a very few seconds after passing the plane of the water level indicated in the water glass.

The formation of foam in an aqueous gas-liquid system may be inhibited by the addition of a compound containing a plurality of hydrophilic nitrogen-containing groups. The preferred compounds within this classification are the acylated polyamides. By the term "acylated polyamides" I mean those compounds resulting from the addition of one or more acyl groups to a compound containing a plurality of amine groups. The polyamine may be simply hydrazine, or an alkylene polyamine such as ethylene diamine or propylene diamine, a polyalkylene polyamine such as diethylene triamine, triethylene tetraamine, tetraethylene pentamine, and the like, or

2

an alkanol alkylene polyamine such as ethanol ethylene diamine.

In general, the most suitable acylated polyamines are the polyalkylene polyamides formed by the acylation of a polyalkylene polyamine with an organic acid containing at least 16 carbon atoms in such proportion that the polyamine is at least diacylated.

The acylating agent may be an organic acid, halide, ester, or acid anhydride, and preferably contains at least twelve carbon atoms. Suitable acylating agents include organic acids such as lauric, stearic, oleic, linoleic, linolenic, palmitic, and ricinoleic acid. The naphthenic acids derived from petroleum are also valuable acylating agents.

Other acylating agents that may be used are the substituted acids, such as ricinoleic acid which has been esterified at the hydroxyl group by means of another organic acid, or an ether substituted hydroxy acid may be used as the acylating agent.

In general, the acylation may be carried out by simply heating one molecular proportion of the polyamine with one or more molecular proportions of the acylating agent at a temperature of about 140° C. or higher.

Experience has shown that steam is contaminated by boiler water in spite of the action of the foam inhibitor. Investigations have proved that such carryover is generally not caused by foam development in the boiler that would reach the steam outlet, but observations of the interior of a boiler with strong back-lighting simulating the dark field illumination provided in ultra microscope studies reveal that the boiler water is entrained in the steam as a dispersion of relatively tiny droplets of boiler water in the steam space above the water surface. In this manner the boiler water leaves the boiler with the steam and enters the super heater units wherein it may cause incrustation or it may be carried over as a dried boiler water constituent to the valves and cylinders of the locomotive where more or less serious impairment of lubrication is experienced, often resulting in excessive wear and breakage of valve bushings and cylinder packing.

The production of such a dispersion of droplets of boiler water in the steam space is primarily the result of a phenomenon which may be termed "effervescence." The effervescence phenomenon will occur from a water surface that is not disturbed by steam bubbles and that is not covered by a layer of foam. Rather, the 55 phenomenon is caused by the dissolved gases contained in the boiler feedwater being forced out of solution by the increased temperature.

The effervescence causes myriads of tiny and even near-microscopic bubbles which rise slowly through the boiler water and break more or less violently at the surface.

A still more potent cause of effervescence is the presence of bicarbonates in the boiler feedwater. These compounds are decomposed upon entering the boiler and mix with the hot boiler water, resulting in the evolution of carbon dioxide in the form of tiny, near microscopic bubbles which, upon rising to the surface, burst with considerable violence to produce a dispersion of water droplets in steam that is quite stable. In this respect, the evolution of carbon dioxide from the boiler water surface tends to produce more effervescence than the liberation of dissolved air. Boiler feedwaters normally containing a high percentage of sodium bicarbonate are especially troublesome in originating effervescence produced by the feedwater entering the boiler below the level of the boiler water surface.

It has been observed that the problem of steam contamination which results in lubrication problems, superheated units, incrustation, etc. is the highest during the winter season. This is to be expected, since during cold weather water can dissolve more air and other gases which would naturally contribute to the effervescence problem.

When acylated polyamine foam inhibitors are added to the boiler feedwater to inhibit foam formation in the boiler, there will be no foam layer in the forward part of the boiler where the feedwater enters and there will be very little, if any, steam bubble generation in that area. However, these conditions are most favorable for the inception of the effervescence phenomenon.

It is an object of this invention, therefore, to provide a composition which will not only inhibit the formation of foam in a boiling water, but will substantially or completely inhibit the effervescence of the boiler water upon heating.

Another object of the present invention is to provide a method for inhibiting foaming and effervescence of aqueous systems which tend to foam on boiling and to effervesce on heating.

I have found that the tendency of the boiler water to effervesce on heating can be completely or substantially inhibited by the addition to the boiler water of a mixture comprising a surface-active, predominantly hydrophilic acylated polyamine foam inhibitor and a surface-tension-reducing agent, or wetting agent. Although wetting agents alone added to boiler feed water act as foam producing agents, there is no such effect when they are added in conjunction with acylated polyamine foam inhibitors. In fact, the foam inhibiting characteristics of the acylated polyamine are in some cases improved, possibly due to the action of the wetting agent in conditioning the steam generating surfaces to facilitate the adsorption thereon of the foam inhibiting chemical.

Experiments have indicated that any stable surface-tension-reducing agent, or wetting agent, that includes a hydrocarbon radical of at least eleven carbon atoms and that, in the case of boiler water or other aqueous systems, is not precipitated by calcium or magnesium salts in the boiler water or by other ingredients contained therein, and that is effective in reducing surface tension and increasing the wetting of the heating surface by the boiler water, increases the efficacy of the various types of acylated polyamine foam inhibitors.

The wetting agents contemplated by my invention include substances such as the fatty alcohol sulfates, sulfated fatty acid amides, sulfated fatty acid esters, secondary alcohol sulfates, sulfated esters of higher molecular weight alcohols and dibasic acids, alkyl aryl sulfonates, sulfonated esters of alcohols and dibasic acids, sulfonated aliphatic esters, sulfated and sulfonated rosin acids, sulfonated aromatic ethers, the alkali metal salts of the above, and other water soluble sulfated or sulfonated organic compounds. Further, non-sulfur containing organic compounds may be utilized as wetting agents. These include compounds such as the partial esters of polyhydric alcohols and fatty acids, ethanolamides of fatty acids, phosphated or phosphorated unsaturated fatty acids, and other compounds characterized by their ability to reduce the surface tension of water and to increase the wetting, penetrating, dispersing, and foaming ability of water. Other classes of compounds which may be used are the aliphatic and aromatic quaternary ammonium compounds. All of these wetting agents are surface-active hydrophilic compounds and are characterized by the presence of a hydrocarbon group of at least eleven carbon atoms and usually by one but not more than two polar groups.

As indicated previously, the addition of a wetting agent to the polyamide foam inhibitor causes a synergistic reaction whereby the polyamides become effective in inhibiting foam in boilers using feedwaters that normally do not respond to the foam inhibitor, such as a feed-water having a relatively low content of dissolved solids.

A very important advantage of the proposed foam inhibiting composition lies in the improvement in the purity of steam generated and withdrawn from the boiler. The mechanism of this function whereby the production of a stable dispersion of water droplets in the steam is inhibited is not definitely known, although it is apparent that a reduction in the surface tension of the boiler water might be expected to result from the addition of the improved foam inhibiting composition to the water. Inasmuch as the effervescence phenomenon is proportional to the surface tension, it is reasonable to expect that the observed improvement in steam quality might be attributed to the reduction in surface tension.

A still further advantage of the foam inhibitor improved by association with a wetting agent or surface-tension-reducing agent is the increase in the efficiency of heat transfer between the boiler metal and the water. It has been demonstrated that the use of a stable wetting agent, such as dodecyl alcohol sulfate, increases the coefficient of heat transfer between the boiler heating surfaces and the boiler water as much as 200 or 400 percent, by actual test. However, the use of such wetting agent alone is impractical because it results in a great increase in the foaming properties of the boiler water. The use of acylated polyamine foam inhibitors in reasonable dosages, such as approximately half the concentration of the wetting agent, suffices to completely inhibit foam formation and still preserves the benefit of the wetting agent by maintaining nuclear type of boiling when steam is generated from the heating surface.

While the compositions of the present invention are particularly adapted for use in locomotive boiler waters, they may also be utilized in water systems operating under atmospheric or sub-

atmospheric pressures, as in cooling systems for diesel engines, in evaporators, or in various industrial processes involving aqueous or non-aqueous systems where foam is a problem.

The wetting agents and/or surface-tension-reducing agents employed in accordance with my invention should preferably be of the type that form soluble salts or compounds with calcium and magnesium. The wetting ability of the agents should also be great enough preferably to decrease the surface tension of the water by at least 25 dynes per centimeter when added in an amount sufficient to give a 1% solution by weight. The wetting agents should have hydrophilic characteristics such that solubilization of sludges precipitated from a hard water will occur with or without the addition of alkaline boiler compounds, so that precipitated material resulting from concentration during steam generation will remain in a more or less fluid state and will not settle and pack at the bottom of the boiler to cause mud burns or otherwise interfere with the free heat transfer from the boiler metal to the water. It is also within the scope of my invention to utilize high molecular weight surface active agents which are not strictly soluble but are colloidally dispersible in hard water.

In addition to the wetting agent and the foam inhibitor, other hydrophilic agents may be added to assure maximum fluidity of the sludge separated out from the water by the boiling and concentration during steam generation. Such additional agents may include hydrophilic colloids of the nature of gum arabic, the alginates, including sodium alginate, seaweed colloidal extracts, lignin or lignin derivatives, tannins, or any highly hydrophilic organic colloid relatively stable under boiler water conditions. Further, basic substances such as soda ash or sodium bicarbonate may be added to help solubilize the sludge. The small amount of bicarbonate added has no appreciable effect on the effervescence inhibiting effect of the compositions.

A particularly suitable composition may be prepared by admixing 4% by weight of the tetranaphthenoyl amide of triethylene tetramine prepared by the acylation of triethylene tetramine with a naphthenic acid derived from petroleum, 1% by weight of oleoyl alcohol sulfate, 25% tannin, and the balance soda ash. The incorporation of 25 parts of the above mixture per million parts water have been found to inhibit foam formation and boiler water carryover.

The compositions may vary over a wide range, but it is preferable that the wetting agent be present in an amount from about one-tenth to about five times the weight of the foam inhibitor in the composition. A relatively higher proportion of wetting agent to acylated polyamine foam inhibitor will be used when the concentration of foam inhibitor is relatively high.

In general, from as little as 1 p. p. m. or less to about 50 p. p. m. of the active foam inhibitor compounds will suffice to inhibit the foaming and effervescence of the boiler water.

In carrying out my invention as applied to locomotive boilers, I prefer to use foam inhibitors of the following types:

Tetrauaoroyl triethylenetetramine.

Triuaoroyl triethylenetetramine.

Tetrauaoroyl tetraethylenepentamine.

Pentauroroyl tetraethylenepentamine.

Dioleoyl diethylenetriamine.

Distearoyl diethylenetriamine.

Distearoyl ethylenediamine.

Distearoyl hydrazine.

Diricinoleoyl ethylenediamine.

Diricinoleoyl diethylenetriamine.

Diricinoleoyl triethylenetetramine.

Tetraricinoleoyl triethylenetetramine.

Triricinoleoyl tetraethylenepentamine.

Disubstituted ricinoleoyl triethylenetetramine.

Disubstituted ricinoleoyl tetraethylenepentamine.

The reaction product of 1 mol of tetraethylenepentamine and at least 5 mols of capric acid.

The reaction product with 1 mol of tetraethylenepentamine with at least 1 mol of castor oil.

The reaction product of 1 mol of triethylenetetramine and at least 2/3 mol of castor oil polymerized with an unsaturated hydrocarbon of not more than 20 carbon atoms.

The reaction product of 1 mol of diethylenetriamine and 2 mols of esterified ricinoleic acid.

The reaction product of 1 mol of ethanol diamine and 2 mols of esterified ricinoleic acid.

Distearoyl hexamethylenediamine.

Diocadecyl adipamide.

Didodecyl sebacamide.

The reaction product of 1 mol of hexamethylene di-isocyanate and 2 mols of stearic acid.

The reaction product of 1 mol of toluene di-isocyanate and 2 mols of ricinoleic acid.

The reaction product of 1 mol of triethylene-tetramine and 4 mols of naphthenic acid (Acid No. 200).

The reaction product of 1 mol of triethylene-tetramine and 3 mols of naphthenic acid (Acid No. 140).

The reaction product of 1 mol of tetraethylenepentamine and 5 mols of naphthenic acid (Acid No. 234).

The wetting agent and/or surface-tension-reducing agent required in the practice of my invention may be any commercial wetting agent that is strongly hydrophilic and stable under boiler water conditions of temperature and alkalinity. The following examples show the classes and types of compounds particularly suitable:

45. High molecular weight alcohol sulfates, preferably containing at least 12 carbon atoms per molecule, e. g., dodecyl alcohol sulfate, tetradecyl alcohol sulfate, hexadecyl alcohol sulfate and octadecyl alcohol sulfate;

50. Substituted long chain alcohol sulfates, such as 12, ethyl ether octadecyl alcohol sulfate and 12, octyl ether octadecyl alcohol sulfate;

55. High molecular weight sulfonic acids and salts, such as lauryl sulfonate and oleoyl sulfonates as well as sulfonates of non-fatty materials such as naphthenic acid sulfonate and alkyl aromatic sulfonates;

60. Quaternary ammonium types of wetting agents, such as cetyl pyridinium bromide, and octadecyl trimethyl ammonium chloride.

The compounds will normally be used in the form of their alkali metal salts. Specific compositions that may be utilized include the following:

	(a)	Per cent
Distearoyl hydrazine	$(C_{18}H_{36}CO-NH-NH-CO-C_{18}H_{36})$	5
70. Sodium lauryl sulfate (Duponol ME)	$(C_{12}H_{25}OSO_3Na)$	2
Tannin type organic matter		20
Lignin derivative		12
Sodium bicarbonate		14
Soda ash		47

(b)

To illustrate the advantage of including the wetting agent in the foam inhibiting composition, the following test was performed.

Foam inhibiting compositions were prepared by mixing 4 parts by weight of the reaction product of 1 molecular proportion of triethylenetetramine and 4 molecular proportions of naphthenic acid having an acid number of 200 with 20 parts tannin material, 12 parts lignin material, and 14 parts sodium bicarbonate. To one-half of the mix thus prepared, 50 parts of soda ash were added. The resulting composition will be designated Sample A. To the other half of the mix, 49 parts of soda ash and 1 part sodium oleyl sulfonate (Duponol LS) were added. The resulting composition will be designated Sample B.

Samples A and B were tested in the same locomotive boiler under identical conditions. Both samples were added in a concentration of 1 pound per 5000 gallons of boiler feed water.

Sample A inhibited foaming until the concentrations of dissolved solids in the boiler water reached 285 grains per gallon. Sample B, containing the added wetting agent, permitted a dissolved solids concentration of 350 grains per gallon without foaming.

Steam sample taken from both runs showed that the steam generated while Sample A was present had a dissolved solids content approxi-

10

mately twice that found in steam obtained during the run using Sample B.

While the compositions of this invention have been particularly described in connection with inhibiting foam and effervescence in boiler water, they also have a beneficial effect in aqueous systems that foam from causes other than boiling, such as from agitation, heating aeration and the like, and in non-aqueous systems that foam or 10 expand excessively due to entrained gases, such as air.

This application is a continuation-in-part of my application Serial No. 305,959, now U.S. Patent No. 2,442,768, issued June 8, 1948.

15 I claim as my invention:

1. A composition for inhibiting foam formation in an aqueous system having a tendency to foam, which composition comprises a polyethylene polyamide having at least 2 acyl groups each 20 having at least 12 carbon atoms and a stable, hydrophilic surface-active organic compound, said surface-active organic compound having sufficient wetting ability to decrease the surface tension of water by at least 25 dynes per centimeter when added to water in an amount sufficient to give a 1% solution by weight, the amount of said surface-active compound being from about one-tenth to about five times by weight of said polyethylene polyamide present.

2. A composition for inhibiting foam formation in an aqueous system having a tendency to foam, which composition comprises a polyethylene polyamide having at least 2 acyl groups, each having at least 12 carbon atoms, and a stable hydrophilic surface-active organic compound selected from the group consisting of alkali metal sulfates of alcohols containing at least 12 carbon atoms and alkali metal salts of organic sulfonic acids, said surface-active organic compound having sufficient wetting ability to decrease the surface tension of water by at least 25 dynes per centimeter when added to water in an amount sufficient to give a 1% solution by weight, the amount of said surface-active compound being from about one-tenth to about five times by weight of said polyethylene polyamide present.

3. A composition for inhibiting foam formation in an aqueous system having a tendency to foam, which composition comprises a polyethylene polyamine having at least 3 acyl groups, each having at least 12 carbon atoms, and a stable hydrophilic surface-active organic compound, said surface-active organic compound having sufficient wetting ability to decrease the surface tension of water by at least 25 dynes per centimeter when added to water in an amount sufficient to give a 1% solution by weight, the amount of said surface-active compound being from about one-tenth to about five times by weight of said polyethylene polyamine present.

4. A composition for inhibiting foam formation in an aqueous system having a tendency to foam, which composition comprises tetranaphthenoyl triethylene tetramine and sodium lauryl sulfate, the amount of said sulfate being from about one-tenth to about five times by weight of said tetranaphthenoyl triethylene tetramine.

5. The method of inhibiting the tendency of an aqueous system to form on boiling, which comprises dispersing into said system a polyethylene polyamine having at least 2 acyl groups, each having at least 12 carbon atoms, and a stable, hydrophilic surface-active organic compound, said surface-active organic compound having sufficient wetting ability to decrease the surface

11

tension of water by at least 25 dynes per centimeter when added to water in an amount sufficient to give a 1% solution by weight, the amount of said polyamine introduced being sufficient to inhibit the tendency of said system to foam on boiling, and the amount of said surface-active agent being from about $\frac{1}{10}$ to about 5 times by weight of the amount of said polyamine present.

6. The method of inhibiting the tendency of an aqueous system to foam on boiling, which comprises dispersing into said system a polyethylene polyamine having at least 2 acyl groups, each having at least 12 carbon atoms, and a stable, hydrophilic surface-active organic compound selected from the group consisting of alkali metal sulfates of alcohols containing at least 12 carbon atoms and alkali metal salts of organic sulfonic acids, said surface-active organic compound having sufficient wetting ability to decrease the surface tension of water by at least 25 dynes per centimeter when added to water in an amount sufficient to give a 1% solution by weight, the amount of said polyamine introduced being sufficient to inhibit the tendency of said system to foam on boiling, and the amount of said surface-active agent being from about $\frac{1}{10}$ to 5 times by weight of said polyamine present.

7. The method of inhibiting the tendency of an aqueous system to foam on boiling, which

5
10
15

12

comprises dispersing into said system a polyethylene polyamine having at least 3 acyl groups, each having at least 12 carbon atoms, and a stable, hydrophilic surface-active organic compound, said surface-active organic compound having sufficient wetting ability to decrease the surface tension of water by at least 25 dynes per centimeter when added to water in amount sufficient to give a 1% solution by weight, the amount of said polyamine introduced being sufficient to inhibit the tendency of said system to foam on boiling, and the amount of said surface-active agent being from about $\frac{1}{10}$ to about 5 times by weight of the amount of said polyamide present.
